UNITED STATES PATENT OFFICE.

EDWIN HAVILAND, OF PLAINFIELD, NEW JERSEY.

DESIGN FOR A PLATTER.

SPECIFICATION forming part of Design No. 15,789, dated February 10, 1885.

Application filed September 15, 1884. Term of patent 7 years.

To all whom it may concern:

Be it known that I, EDWIN HAVILAND, a citizen of the United States, residing in Plainfield, in the county of Union and State of New Jersey, have invented or produced a certain new and original Design for Platters, of which the following is a specification.

Figure 1 of the accompanying drawings is a plan view of a platter embodying my design. Fig. 2 is a longitudinal section thereof on line 2 2, and Fig. 3 is a transverse section thereof on line 3 3.

The platter embodying my design is in general of elongated rectangular outline in plan, having straight sides, rounded corners, and straight ends, with ornamental handles. The side outlines, *a a*, are straight and join the curved or nearly semicircular corners *b b*, with indentations *c c*, and the end outlines, *d d*, appear to extend likewise in a straight line; but the greater portion of the end of the dish is occupied by the ornamental handle *H*, which appears to be mounted upon and to cover and conceal a portion of the end of the dish proper. The depressed central portion, *A*, of the platter is flat, and is outlined by straight side lines, *e e*, and straight end lines, *f f*, joined by short quarter-circles or curves *g g*, without indentation or other interruption. The flange *B* of the platter extends upward from the portion *A* in straight lines, (in cross-section,) and at the angle shown in Figs. 2 and 3. The dish having this shape and outline embodies one of the segregable features of my present design and presents a pleasing angular appearance, different from that of any other platter, so far as I am aware. The handles *H H* form an upward continuation of the ends of the platter and terminate in a somewhat irregular curved outline, *h h*. The handle is not detached or insulated from the end of the platter, but is merged therewith and appears as a raised ornament thereon. Underneath it is concaved at *i* in Fig. 2, and on the upper side it is correspondingly convexed. The pattern of the handle is in low relief. From each side of the handle and along the outline *d* a row of beaded or rope-like corrugations, *j*, proceeds and extends toward the middle, and the two rows *j j*, after thus approaching each other, curl downward and out-

ward upon the end of the platter, as shown. Between them and outside of them is a convex space, *k*, devoid, or nearly so, of ornament. At its root this space terminates in a trefoil, *l*, from the middle of which, and apparently from beneath it, an ornamentation consisting of a trident-shaped group of stems projects and descends to a leaf, *m*. The middle of the three stems is the stem for this leaf. The two outer stems apparently pass beneath the leaf, and upon their reappearance they extend in graceful curves to each side in a simulation of budded stems or tendrils *n n*. The portion of this handle ornamentation which is identical with that shown in my Patent No. 14,948, dated April 8, 1884, for "Design for Earthenware Dishes," I do not now claim. The distinctively new feature of this handle I believe to be the configuration of the handle as an uninsulated continuation of the end of the platter, and also the configuration of the two rows of corrugations *j j*, with the convex smooth surface *k* between and outside of them.

What I claim as new, and desire to secure by Letters Patent, is—

1. The design for a platter herein shown and described, the same consisting of flat bottom *A*, of elongated rectangular outline, having straight sides and ends, and inclined flange *B*, bordering said bottom, extending upward therefrom in straight lines, and terminating in an exterior outline consisting of straight sides and ends, with rounded corners joining them through indentations.

2. The design for a platter herein shown and described, the same consisting of an elongated rectangular outline with rounded corners, straight sloping flanges *B*, and handles *H H* on the ends in low relief, appearing as continuations of the end flanges and terminating with the rounded outlines *h h*.

3. The design for a platter herein shown and described, the same consisting of an elongated rectangular outline with rounded corners and end handles, *H*, appearing as a continuation of the ends, merged therewith without being raised or insulated therefrom, and each having concave under side, *i*, and convex upper side, *h*.

4. The design for a platter herein shown

(over)

and described, the same consisting of the configuration of the handles, with two rows of beaded or rope-like corrugations, *j*, *j*, extending toward each other, then curving inward, 5 downward, and outward on the surface of the platter, and the smooth concave portions *k* between the corrugations, extending beyond them and terminating in a curved outline, *h*.

In witness whereof I have hereunto signed my name in the presence of two subscribing to witnesses.

EDWIN HAVILAND.
